UNITED STATES PATENT OFFICE.

EMIL JOSSE, OF WILMERSDORF, GERMANY.

VAPORIZER FOR COLD VAPORS OR THE LIKE.

SPECIFICATION forming part of Letters Patent No. 708,647, dated September 9, 1902.

Application filed May 17, 1901. Serial No. 60,645. (No model.)

To all whom it may concern:

Be it known that I, EMIL JOSSE, a subject of the Emperor of Germany, residing at Wilmersdorf, Germany, have invented certain new and useful Improvements in Vaporizers for Cold Vapors or the Like, of which the following is a specification.

This invention relates to a new arrangement of vaporizing apparatus which is chiefly intended for cold vapors, its object being to utilize the heat of the heating medium in a plain or uniform apparatus or cylinder as far as possible and until the vapors obtained are superheated.

15 The essential feature of the present invention is that the vaporizing-chamber, which is traversed by a series of small horizontally-arranged tubes and in which the counter-current principle is employed, is provided in or 20 toward its lower half with one or more horizontal partitions, so that the fluid in the evaporator is in a cooler state in the lower layers, whereas a temperature corresponding to the 25 pressure of the condenser is obtained in the upper part, the vapors being, in fact, moist in the lower layers, dry in the middle, and superheated in the upper. This division can be effected by means of any insulating-walls rendered adjustable, if so desired.

30 Upon the annexed drawings the new vaporizer is shown in one form by way of example.

Figure 1 is a longitudinal sectional elevation, and Fig. 2 is a cross-section.

35 The cylinder *a* is closed at the ends by the tube-plates *b b*, through which the heating-tubes *c* are passed and suitably secured, so that the interior of the tubes communicates with the chambers *d*, which are formed by 40 attachments or covers *e e* at the two ends. Into one of these chambers *d* the heating medium, such as exhaust-steam from a steam-engine or the like, is admitted in order that it may pass through the tubes *c* and in a direction contrary to that in which the fluid to be heated traverses the chamber *a*. This is insured by a suitable number of partitions *i* in the chambers *d d*, which determine the path for the heating medium.

45 The fluid to be vaporized—sulfurous acid, ammonia, and the like—flows into the actual vaporizing-chamber *a* from below at *n*. This

chamber, however, does not form an uninterrupted space in which a change of temperature would be quickly effected, but is provided near its bottom with a horizontal partition *f*, which allows communication only with the upper chamber at one end *o* opposite to the inlet-opening *n* for the fluid. Here accordingly the fluid remains in a condition 60 which, compared with that in the upper part, may be described as "undercooled." This effect may be increased by means of a second partition, which separates the fluid above from the condensing-chamber and forces it 65 to flow over the first partition *f* to the other side. A second suitable perforated partition *g* may be arranged in the upper part of the chamber beneath the upper row of the tubes in order to prevent the immediate or a too- 70 sudden change or to retard it. Under certain circumstances the separation by means of the very small tubes or a series of horizontal tubes suffices for the purpose. The level of the fluid to be vaporized should be so regulated that the uppermost tubes traversed by the entering—that is, the hottest—steam should pass through the vapor-space, so that they can superheat the vapor. The superheated vapor collects in the upper part of the 75 chamber *a* and in the dome *h*, whence it is conveyed to its working cylinder. In this way the difference of temperature, which otherwise must amount to about 10° centigrade between the heat of the exhaust-steam and 80 the boiling-point of the fluid to be vaporized, can be utilized to within about 2°.

Having described my invention, what I claim, and desire to secure by Letters Patent, is—

1. A vaporizer, comprising a chamber or casing provided with an inlet and an outlet, heating-tubes extending through said chamber, and a partition located in the chamber between the inlet and the outlet, to retard the 95 flow of the fluid through the chamber.

2. A vaporizer, comprising a chamber or casing provided with an inlet and an outlet, heating-tubes extending through said chamber, and a partition located in the chamber 100 between the inlet and the outlet and extending lengthwise of said tubes, to divide the said chamber into a preheating-compartment and a vaporizing-compartment.

3. A vaporizer, comprising a chamber or casing provided with an inlet and an outlet, heating-tubes extending through said chamber, a partition located in the chamber between the inlet and the outlet, to divide said

5 chamber into a preheating-compartment and a vaporizing-compartment, and a perforated partition located between the first-named par-

tition and the outlet, whereby a superheating-compartment will be formed adjacent to the outlet.

EMIL JOSSE.
